UNITED STATES PATENT OFFICE.

OTTO QUANTE, OF PHILADELPHIA, PENNSYLVANIA, ASSIGNOR TO DILL AND COLLINS CO., OF PHILADELPHIA, PENNSYLVANIA, A CORPORATION OF PENNSYLVANIA.

DOCTOR FOR CALENDER ROLLS.

Application filed August 26, 1922. Serial No. 584,394.

To all whom it may concern:

Be it known that I, OTTO QUANTE, a citizen of the United States, and a resident of Philadelphia, in the county of Philadelphia and State of Pennsylvania, have invented an Improvement in Doctors for Calender Rolls, of which the following is a specification.

In the manufacture of paper it is necessary that the surfaces of the calender rolls of calendering machines shall be kept clean and free from small particles of any kind or character, otherwise the paper which may run through or over such rolls is apt to be injured, which may result in serious loss to the manufacturer.

Various forms and constructions of cleaning doctors for calender rollers heretofore have been constructed and employed but none of them have been entirely satisfactory in operation. One of the reasons for this has been the failure to provide a structure in which the portion thereof which is adapted to contact with the surface of the roll may be caused to properly adjust itself to all portions of the surface thereof even though they may occupy unequal distances from the axis thereof.

The present invention has for its general object to provide a construction of cleaning doctor for calender rolls which although novel is simple in construction and may be economically manufactured.

A further object of the invention is to provide a cleaning doctor for calender rolls having improved and novel means whereby the opposite ends thereof are independently adjustable so that all parts of the portion of the said doctor which is adapted to contact with the surface of the roll may engage said surface, notwithstanding the fact that portions thereof may not be parallel with the axis of the roll.

To these and other ends the invention comprehends the construction and arrangement of parts as will be hereinafter fully described in the specification and as illustrated in the drawings forming a part of this specification, and in which one form of mechanical embodiment of the invention is shown. However, it will be understood that the invention is susceptible of embodiment

in other forms of construction than that shown and that various changes in the details thereof may be made within the scope 55 of the claims without departing from the said invention.

In the drawings:—

Fig. 1 is a horizontal sectional view taken on the line 1—1 of Fig. 2, the said view 60 showing a portion of a calender roll in top plan and also showing the doctor in top plan;

Fig. 2 is a transverse sectional view taken on the line 2—2 of Fig. 1;

Fig. 3 is a view similar to that shown in Fig. 2 but with the operative parts of the doctor in different position from that shown in Fig. 2;

Fig. 4 is a view in rear elevation of a 70 portion of the doctor at the right hand end thereof showing certain details of construction more clearly;

Fig. 5 is a transverse sectional view taken on the line 5—5 of Fig. 4; and

Fig. 6 is a transverse sectional view taken on the line 6—6 of Fig. 4.

Referring to the drawings, 1 designates frame members of the calender machine structure situated in front of the opposite 80 end portions of the calender rolls 2, one of which is shown in the drawings. Anchoring or connecting plates 3 are secured to the inner sides of these frame members 1 by means of screws 4 and to the said anchorage 85 or connecting members 3 arms 5 are pivotally and swingingly secured or connected by means of bolts 8 retained in position by means of nuts 9. The said bolts are provided with extensions 10 upon their inner 90 ends around which are coiled springs 11. One end of each of these springs extends through a hole 12 in the extension with which such springs are associated. The opposite ends of the springs are extended as indicated at 15 and contact with headed screws 16 or projections of any other character upon the inner sides of the arms 5 a considerable distance from the pivotal axes thereof, as shown. These springs tend to 100 hold the arms forwardly toward the calender roll 2 in the position as shown in Figs. 1 and 2 of the drawings.

The upper ends of the arms 5 are pro-

vided respectively with inwardly extending portions 20 to which the opposite ends of a plate 21 are secured. For the purpose of effecting connection between the opposite ends of said plate and the inwardly extending portions 20, the latter are provided with slots 22, while the plate 21 is provided near its opposite ends with circular openings 23. Screw-threaded bolts 25 extend through the openings 23 and the slot 22 and are retained in place by means of nuts 26. These bolts are in parallel relation practically to the arms 5 so that the angularity of the plate 21 to said arm may be varied as occasion may require in the operation of the device. The upper ends of these bolts are provided with relatively wide heads 27 which are adapted to retain the plate 21 in position upon the inwardly extending portions 20 of the arms 5. Directly underneath the relatively wide heads 27 are similar heads 30 of diameters slightly less than the diameters of the openings 23 in the plate 21 in which they are situated, but 25 of greater diameter than the width of the slots 22. By this arrangement it will be seen that the bolts 25 may be clamped immovably and rigidly to the inward extensions 20 of the arms 5 at any point desired 30 within the slots 22. The heads 30 are of a height or thickness such as to prevent the clamping of the heads 27 tightly against the top surface of the plate 21, hence it will be seen that the latter is pivotally related to 35 the inward extensions 20 of the arm 5. This relationship between these parts permits independent automatic adjustment of the opposite end portions of the plate 21 which supports and carries the cleaning portion 40 of the doctor, which will be hereinafter described. An angle member 35, somewhat shorter than the plate 21, is secured to the outer upper edge of the latter. The inner flange of this angle plate extends upwardly 45 and vertically with respect to the plate 21, as is clearly shown in Fig. 6 of the drawings.

A cleaning pad 36 of felt or other suitable material is mounted upon the upper side of the plate 21 in front of the upright flange of 50 the angle plate 35. The outer edge of the cleaning pad 36 is seated against the inner side of the said vertical flange. The said pad projects a considerable distance forwardly of and beyond the inner edge of the 55 plate 21, as shown. For the purpose of securing the cleaning pad 36 upon the plate 21 I have provided a thin metal strip 37 upon the upper side of the inner portion of the latter, which is secured in place by 60 means of screws 38. The inner edge of the said strip 37 is provided with an upwardly turned serrated flange forming teeth 39 which are adapted to enter the bottom or under side of the pad 36 to aid in holding 65 the same in place, as clearly indicated in

the drawings. For engaging the upper side of the pad I have provided a plate 40, the inner edge of which is provided with a downwardly turned serrated flange, the teeth 41 of which enter and engage the upper portion of the pad, as shown. The outer edge portion of the said plate 40 is secured to a narrow relatively thick plate or bar 42 to which finger-pieces 43 are secured at intervals. The said finger-pieces are also connected with the outer end portions of plate springs 44, the inner lower ends of which are secured to the upright flange of the angle plate 35 by screws or otherwise as may be desired. For the purpose of pivotally connecting the plate or bar 42 and the parts carried thereby, including the plate 40, to the angle plate 35, I have provided angle brackets 45 arranged in couples, as shown, which are secured to the outwardly horizontally extending flange of the said angle plate, and angle brackets 46, similarly arranged in couples, which are secured to the under side of the plate or bar 42. The upwardly extending portions of the angle 80 brackets 45 of each couple overlap the downwardly extending portions of the corresponding couples or brackets 46 which are secured to the plate or bar 42 and the said overlapping portions are connected together 85 by a pivot rod 48. These pivotal connections, as well as the finger-pieces 43 and the springs 44, heretofore referred to, are situated at intervals in order to effect a more satisfactory operation of the plate 40.

It will be noted that the finger-pieces 43, and springs 44, are situated at intervals intermediate the angle brackets 45 and 46 of the respective couples. It will also be noted that the springs 44 have a tendency to 105 straighten out whereby the plate 40 automatically clamps and engages the pad 36, as shown in the drawings. It will also be apparent that the plate or bar 42 may be readily actuated by means of the finger-pieces 43 to open the spring-pressed plate 40 to permit the removal of a pad from or the insertion of the same into position above the inner portion of the plate 21 and against the inner side of the upright or vertical 115 flange of the angle plate 35.

For the purpose of retaining the arms 5 in position to hold the pad 36 out of contact with the roller 2, I have provided arms 50 which are pivotally connected at 51 to the arms 5 a distance above the pivotal connection of the latter to the anchorages or connections 3. These arms 50 are provided with hooks 52 which are adapted to engage notches 53 in the outer ends of the anchorages or connecting plates 3. The said hooks 52 are shown in engagement with the notches 53 in Fig. 3 of the drawings.

To limit the outward swinging movement of the arms 5 they are provided with 130

contact portions 54 which contact with stops 55 as shown in Fig. 3 of the drawings.

It will be apparent that by my invention I have provided a construction of calender doctor in which the outer end portions thereof are independently and automatically adjustable with respect to each other, whereby the cleaning pad carried thereby is adapted to adjust itself to the surfaces of the rolls 10 regardless of any inequalities which may be present thereon and regardless of whether or not the portions of surfaces at the opposite ends of the roll are at unequal distances from the axis of such roll.

Having thus described my invention, what I claim and desire to secure by Letters Patent is:

1. In a doctor for calender rolls, the combination of a pad, pivoted arms, and means 20 for pivotally and operatively connecting the outer swinging ends of said arms to the said pad, said means being parallel practically with said arms.

2. In a doctor for calender rolls, the combination of a pad, means for holding the said pad, separate and independent pivoted means, and means for pivotally connecting the said pivoted means to the said holding means, the last named means being practically parallel with the second named means.

3. In a doctor for calender rolls, the combination of a cleaning member, means for holding the same, and pivotally supported arms having pivotal connection with the said holding means at the opposite ends thereof, whereby the angularity of said arms with respect to said holding means may be varied.

4. In a doctor for calender rolls, the combination of a cleaning pad, holding means therefor, pivotally supported arms, and pivots for pivotally connecting the outer swinging ends of said arms to said pad supporting means, said pivots being practically parallel relation to said arms.

5. In a doctor for calender rolls, the combination of a cleaning pad, holding means therefor, arms supported at their outer lower ends upon stationary pivots, the said arms having inwardly extending projections at their upper ends upon which the said pad supporting means is supported, and means for pivotally and adjustably connecting the said pad supporting means to the said inwardly extending projections.

6. In a doctor for calender rolls, the combination of means for holding a cleaning member, pivoted arms having connection at their outer swinging ends with the said means for supporting the said cleaning member, the said arms being adapted to swing toward and from a calender roll, and means for holding the said arms and the said supporting means in a position remote with respect to the said roll.

7. In a doctor for calender rolls, the combination of a cleaning pad adapted to bear upon the surface of a rotating calender roll to clean the same, holding means for the said pad, arms pivotally connected at their outer ends for supporting said holding means, means for pivotally connecting the inner swinging ends of said arms to said holding means, and yielding means for pressing the said arms toward the said calender roll to press the said pad against said roll.

8. In a doctor for calender rolls, the combination of a cleaning pad adapted to bear upon the surface of a rotating calender roll to clean the same, holding means for the said pad, arms pivotally connected at their outer ends for supporting said holding means, means for pivotally connecting the inner swinging ends of said arms to said holding means, yielding means for pressing the said arms toward the said calender roll to press the said pad against the said roll, and means having connection with said arms for holding the said arms and the pad carried thereby out of operative position with respect to the said rolls.

9. In a doctor for calender rolls, the combination of a pad, a base on which said pad is supported, a spring-pressed clamp for clamping and securing said pad to said base, parallel arms pivotally supported at their lower outer ends in spaced relation to each other, and means for pivotally connecting the upper inner swinging ends of said arms to the said base.

10. In a doctor for calender rolls, the combination of a pad which is adapted to contact with the surface of a calender roll to clean the same, a plate upon the top side of which the said pad is secured, the inner edge of which plate is in parallel relation to the surface of the adjacent calender roll, an angle iron supported upon the upper side of the rear edge portion of said plate, the inner flange of said angle iron being vertical to the said plate, a clamping plate for clamping the said pad to the said pad supporting plate, means arranged at intervals for pivotally connecting the said clamping plate to the said angle iron, springs arranged at intervals for pressing the inner edge portion of the said clamping plate yieldingly against the said pad, arms situated in spaced relation to each other and pivotally supported upon stationary pivots at their lower ends, and means for pivotally connecting the upper ends of said arms to the opposite end portions of the said pad supporting plate.

11. In a doctor for calender rolls, the combination of holding means for a cleaning pad, arms situated in spaced relation to each other for supporting said holding means, means for connecting the upper ends

of said arms to said holding means, connecting plates between said posts and the said arms which plates are provided with notches in their outer ends, pivots for connecting the lower ends of said arms to said connecting plates, catch arms having pivotal connection with the said arms, the catches upon the said catch arms being adapted to

engage the said notches to hold the first-named arms and the cleaning pad carried thereby in inoperative position.

In testimony that I claim the foregoing as my invention, I have hereunto signed my name this 24th day of August, A. D. 1922.

OTTO QUANTE.
